Filed Aug. 13, 1963, Ser. No. 76,195

Term of patent 14 years

(Cl. D3—25)

FIG. 1.

FIG. 2.

FIG. 3.

FIG. 4

FIGURE 1 is a front elevation of a foam rubber wet suit shirt showing my new design;

FIGURE 2 is a side elevation thereof;

FIGURE 3 is a rear elevation of the foam rubber wet suit shirt with one arm in a raised position; and

FIGURE 4 is a side elevation thereof.

The characteristic feature of my design resides in the combination on the foam rubber wet suit shirt disclosed of the the specific panel effect on the front as outlined by the decorative stitching, together with the harmonizing rear panel effect, all as shown.

I claim:

An ornamental design for a foam rubber wet suit shirt, substantially as shown and described.
